UNITED STATES PATENT OFFICE.

CARL WOWRA, OF CHICAGO, ILLINOIS.

CURTAIN-POLE HANGER.

No. 902,635.

Specification of Letters Patent.

Patented Nov. 3, 1908.

Application filed May 25, 1908. Serial No. 424,978.

To all whom it may concern:

Be it known that I, CARL WOWRA, a citizen of the United States and residing at Chicago, in the county of Cook and State of Illinois, have invented a new and useful Improvement 5 in Curtain-Pole Hangers, of which the following is a complete specification.

This invention relates to improvements in curtain pole hangers and more particularly 10 to a curtain pole hanger of that class adapted to lower the pole when it is desired to remove the curtain from or place it upon the pole. Heretofore curtain pole hangers of this class have been devised but they have 15 usually been provided with cords and pulleys for the purpose of raising and lowering and supporting them in their adjusted positions. In such constructions it is necessary that the cords be kept properly adjusted to hold the 20 hangers in true relation to each other, and it is also necessary to secure the cord after the curtain has been adjusted to prevent further movement.

The object of this invention is to provide a 25 curtain pole hanger adapted to raise and lower the curtain without the use of supporting cords or other similar devices which it is necessary to secure to hold the curtain in its adjusted position.

It is also an object of the invention to provide a curtain pole hanger adapted to be locked in its lowermost position, and which, when released, will automatically return to 35 its upright position and carry the curtain upwardly to its position in front of the window or other opening which it is to screen.

It is a still further object of the invention to provide a device in which the tension of the raising mechanism may be adjusted to regulate 40 the folding movement of the hanger so as to adapt it to curtains of different weights.

The invention consists of the matters hereinafter described in the specification and more fully pointed out and defined in the appended claims.

In the drawings: Figure 1 is a perspective view of a window provided with a pair of curtain hangers embodying my invention. Fig. 2 is a fragmentary, side elevation, 50 partly in section, of one of the hangers. Fig. 3 is a fragmentary, front elevation of the hanger showing the arm in elevated position and the casing in section. Fig. 4, is an end elevation of the sliding collar. Fig. 5 55 is a perspective view of the ferrule for the curtain pole.

As shown in said drawings: A indicates a window, at either side of which is a curtain pole hanger indicated as a whole by B and on which the curtain pole C is hung. 60 Said hangers are identical in construction so that a description of one will suffice for both, and, as shown more clearly in Fig. 2, b indicates an attaching plate of any preferred construction and material adapted to 65 be rigidly engaged to the wall or other support at one side of the window. Near the bottom of said plate is a forked stud b' which is riveted or otherwise rigidly secured thereto, and pivoted in the fork of said stud 70 is a threaded adjusting bolt b². Adjustably engaged on said bolt is an arm B', which may be of any preferred construction but which, as shown, comprises a plurality of telescoping sections secured together by 75 means of collars b³ on the overlapping ends of the sections and having set screws b⁴ which extend therethrough into engagement with the inclosed ends of the sections. In the rear end of said arm is rigidly engaged a 80 nut b⁵ which has threaded engagement with said bolt and is provided with a flange which projects laterally beyond the arm. Slidably engaged on said arm is a collar D having apertured lugs d thereon between which is 85 pivoted one end of a joint bar d', the other end of which is pivoted to a lug d² near the upper end of the attaching plate b. Said bar d' is provided with a central joint d³ which breaks downwardly, and when the 90 two sections of the bar are in alinement, as shown in Fig. 2, the arm B', bolt b² and stud b' are held in approximately axial alinement. On each side of said arm B' is a connecting bar d⁴, the forward ends of which 95 are pivoted to the sides of the collar D by means of pins d⁵. Said bars extend rearwardly and upwardly and are pivoted to lugs d⁶ on the plate b and which are located above the stud b'. A coiled spring E is carried on said arm and engages at one end against the flange of the nut b⁵ and at the other end against the collar D, and acts normally to force the collar longitudinally of the arm. A casing F, which, as shown, is 105 open at its ends and on one side, incloses the rear portion of said arm and is pivoted at its rear end to ears f on said plate slightly above the stud b', and at its forward end is provided in its sides with slots f' through 115 which the pins d⁵ extend to support the forward end of the casing. On the forward end

of said arm is a hook G, having a bearing seat g thereon, formed by the inturned end g' of the hook at one end, and by a shoulder g^2 at the other, and slidably engaged therein 5 is a ferrule H adapted to support one end of the curtain pole. Said ferrule is provided with a T shaped member adapted to slidably engage on said seat and the shank h of said T shaped member is slotted to receive the 10 hook G therethrough, and the ends of the cross head h' are slotted to straddle said hook so as to prevent the ferrule from swinging laterally, but permitting it to slide on said seat when the arm B' is operated. 15 Any preferred means may be provided to lock the arm in upright position but, as shown in Fig. 3, a notched catch I is engaged to the plate b near the top thereof, and a curved lever I' is pivoted on the plate on 20 the opposite side of the arm from said catch, and is adapted to be turned in front of the arm when the latter is raised and to engage in said catch.

The operation is as follows: When it is 25 desired to adjust the curtain J upon the pole, or to remove it from or place it upon the pole, the arms B' are swung downwardly, as shown in Fig. 1, thereby lowering the pole sufficiently to enable a person to reach 30 it from the floor. When in this position the spring E is under tension and is exerting pressure against the collar D, but the joint bar d' being now straightened out prevents movement of the collar and consequently 35 prevents the arm from returning to its upright position. When however the joint d^3 of said bar is pulled downwardly the arm is turned upwardly out of alignment with the stud b' and the spring acting on said collar tends to force the latter longitudinally 40 of the arm. Inasmuch as the connecting bars d^4 tend to prevent the collar from moving farther away from the plate b , and inasmuch as they are pivoted at their rear ends 45 above the pivotal point of the arm, they act to swing the arm inwardly against the plate as the spring forces the collar longitudinally of the arm. This action is caused by the fact that when the bars d^4 assume an up- 50 right position the distance between the pivotal point of the arm and the collar is greater than when the arm is down, thereby permitting expansion of the spring when the arm is raised and contraction when it is lowered. 55 The tension of the spring may be regulated by adjusting the arm on the bolt b^2 . When the arms assume an upright position the T members of the ferrules slide in the bearings g of the hooks G and thereby retain their 60 vertical positions.

Obviously the arms B' may be adjusted to make them any desired length and obviously also many details of form and construction may be varied without departing from the 65 principles of my invention.

I claim as my invention:

1. In a device of the class described the combination with an arm of means pivotally supporting the same, means adapted to lock said arm in a horizontal position and means adapted to automatically throw said arm to an upright position when said locking means is released. 70

2. In a device of the class described the combination with an arm of means pivotally supporting the same, means adapted to lock said arm in a horizontal position and an adjustable spring adapted to automatically raise the arm when the lock is released. 75

3. In a device of the class described the combination with an attaching plate of an arm pivoted thereon, a collar slidably engaged on said arm, means adapted to lock said collar from movement when the arm is in one position and means acting on said collar and adapted to automatically raise the arm when said lock is released. 80 85

4. In a device of the class described the combination with an attaching plate of an arm pivoted thereon, a collar slidably engaged on said arm, a spring on said arm adapted to engage said collar and means acting on said collar to compress the spring when the arm is swung downwardly on its pivot and to release the spring when the arm is swung upwardly. 90 95

5. In a device of the class described the combination with an attaching plate of an arm pivoted thereon, a slideable collar on said arm, means connecting said collar with said plate and a spring on the arm engaging against said collar and adapted to swing the arm to its upright position. 100

6. In a device of the class described the combination with an attaching plate of an arm pivotally connected therewith, a collar slidably engaged on said arm, a joint bar connecting said collar and said plate and adapted when in one position to lock the arm from movement, connecting bars connecting said collar with said plate, a spring on said arm and engaging said collar, and means for regulating the tension of said spring. 105 110

7. In a device of the class described the combination with an attaching plate of an adjusting bolt pivoted thereon, an arm engaged on said bolt, a collar slidably engaged on said arm, a spring on said arm acting normally to force said collar longitudinally of the arm, means connecting said collar with said plate and acting to compress the spring when the arm is lowered and means for locking the arm against movement when in its lowermost position. 115 120

8. In a device of the class described the combination with an attaching plate of an arm pivoted thereon, a slideable collar on said arm, a spring acting against said collar, connecting bars connecting said collar with 125 130

said plate and acting when the collar is moved by said spring to raise the arm, means for locking the arm in its lowermost position and a casing inclosing the rear portion of said arm.

9. In a device of the class described the combination with an attaching plate of an arm pivoted thereon, means adapted to automatically raise said arm to a vertical position, means adapted to lock the arm in a horizontal position, a hook on the outer end

of said arm, a ferrule and means connecting said ferrule with said hook, adapted to permit the ferrule to retain its vertical position but prevent it from swinging laterally.

15

In testimony whereof I have hereunto subscribed my name in the presence of two witnesses.

CARL WOWRA.
